UNITED STATES PATENT OFFICE.

GEORGE WHITE, OF SAN FRANCISCO, CALIFORNIA, ASSIGNOR OF ONE-HALF
TO EDMUND H. BUCKNAM, OF SAME PLACE.

FOG-HORN.

SPECIFICATION forming part of Letters Patent No. 357,802, dated February 15, 1887.

Application filed February 24, 1886. Serial No. 193,068. (No model.)

To all whom it may concern:

Be it known that I, GEORGE WHITE, of the city and county of San Francisco, State of California, have invented an Improvement in 5 Fog-Horns; and I hereby declare the following to be a full, clear, and exact description of the same.

My invention relates to certain improvements in fog-horns, such as are used on vessels 10 and at other points during foggy weather.

It consists, of a chamber having a mouth-piece at one end, an organ or other reed adjustably fitted to the opposite end, and an intermediate chamber or chambers with tortuous 15 passages and screen-openings, through which the air reaches the reed from the mouth-piece, and, in connection with this, of a secondary perforated chamber, which may be filled with sponge or other porous moisture-absorbing 20 material.

Referring to the accompanying drawings for a more complete explanation of my invention, Figure 1 is a longitudinal vertical section on the line *x x* of Fig. 2, taken transversely 25 across the reed and interior chambers. Fig. 2 is a longitudinal section of the fog-horn complete. Fig. 3 is a longitudinal section on the line *y y* of Fig. 1, taken longitudinally through the reed and the interior chamber.

30 In the construction of horns for the above-mentioned and other purposes, it is usual to fix a reed directly inside the mouth-piece, and the reed thus placed is subjected to the action of a great amount of moisture from the breath, 35 which is apt to corrode and is also very apt to become clogged on account of the propensity of sailors to chew tobacco, particles of which become blown into the reed, thus preventing its action. In order to protect the reed from 40 these difficulties, I place it in a chamber situated at a considerable distance from the mouth-piece.

In the present case, A is a chamber of considerable length, fixed at the upper end of the 45 horn, having a mouth-piece, B, fitted to one end. In the lower end of this chamber is a disk or diaphragm, C, having a beveled guide or channel, D, extending across it for the reception of an ordinary organ-reed, E. The exterior of 50 the chamber is perforated at this point and provided with a screw-cap, A', which may be

taken off, thus exposing the end of the reed, which is thus easily drawn from the chamber and its guide for repairs and for cleaning. From the guide D, in which the reed is held, a tube, 55 F, extends upward, this tube being elliptical in shape and corresponding with an opening in the diaphragm at the back of the guide, having a length equal to the reed. The tube extends upward into a surrounding oval chamber, G, the upper part of which is closed tight by a cap, G'. Upon the bottom of this chamber, surrounding the tube F, is a perforated screen, H, situated at a little distance from the diaphragm or plate C carrying the reed. 60 The diaphragms or disks C and H fit closely inside the exterior chamber, A, and the chamber G projects upward into the chamber A, as shown, there being a space around each side of it, so that when air is blown into the 65 chamber A through the mouth-piece it passes down through the perforated gauze screen H, thence upward into the chamber G, and down through the elliptical tube F, so as to pass 70 through the reed and thence into the trumpet end of the horn. By thus causing the air to pass through a tortuous passage it is relieved of considerable moisture, and any solid particles which may be blown into the chamber A will be caught and detained upon the 75 perforated diaphragm H.

In order to still further protect the apparatus from solid matter, and to deprive the air of a considerable portion of the moisture which is ordinarily carried by the breath, I fit 80 a short tubular chamber, I, into the upper part of the chamber A, just inside of the mouth-piece. The sides of this chamber, and the bottom, if desired, are perforated with holes, and its interior is filled with sponge or other porous material, which will absorb and retain the moisture which is blown into it, while at the same 85 time allowing air to pass through it freely for the purpose of operating the reed. By this construction I am enabled to overcome most of 90 the objections which have hitherto arisen to this class of devices.

Having thus described my invention, what I claim as new, and desire to secure by Letters Patent, is—

1. An exterior chamber having a mouth-piece at one end and a reed fitted at the other,

in combination with a tube extending inwardly from the reed, a surrounding chamber with the top and sides closed, and a perforated diaphragm or screen opening at the bottom, 5 arranged in the air-passage, substantially as herein described.

2. In a fog-horn, the exterior chamber having a mouth-piece at one end, a disk or diaphragm closing the opposite end, and a guide 10 extending transversely across the disk, in combination with a reed removably fitted to said holder, substantially as herein described.

3. In a horn, a chamber having a mouth-piece at one end and a diaphragm closing the 15 opposite end, and a guide into which a reed may be removably fitted, the diaphragm being perforated at the back of the guide for the admission of air, in combination with a cap fitted to the side of the exterior chamber opposite the end of the reed, substantially as herein described.

4. In a horn, an exterior chamber having a mouth-piece at one end and a reed fitted into the opposite end, in combination with a supplemental cylinder or chamber fitted into the 20 25

exterior chamber near the mouth-piece, said chamber being perforated and filled with a spongy material, substantially as herein described.

5. In a horn, an exterior chamber having a 30 mouth-piece at one end, the other end closed by a diaphragm or disk, a guide fitted transversely of said disk, in which a reed is removably fitted, a perforation in the diaphragm corresponding with the reed and having a tube 35 extending inwardly from it, and an inclosing-chamber for said tube with a perforated diaphragm or disk forming its lower end, through which air may enter from the exterior chamber, in combination with a cylindrical perforated 40 chamber fitted near the mouth-piece and containing a spongy substance, substantially as herein described.

In witness whereof I have hereunto set my hand.

GEORGE WHITE.
